UNITED STATES PATENT OFFICE.

LENNY R. WINSLOW, OF CHICAGO, ILLINOIS, ASSIGNOR TO TRIUMPH VOTING MACHINE COMPANY, OF PITTSFIELD, MASSACHUSETTS, A CORPORATION OF NEW JERSEY.

VOTING-MACHINE.

1,095,689.

Specification of Letters Patent.

Patented May 5, 1914.

Original application filed January 2, 1909, Serial No. 470,411. Divided and this application filed August 9, 1909. Serial No. 511,878.

To all whom it may concern:

Be it known that I, LENNA R. WINSLOW, a citizen of the United States, residing at Chicago, in the county of Cook and State of Illinois, have invented a new and useful Improvement in Voting-Machines, of which the following is a specification.

My invention relates particularly to restrictive devices adapted to regulate the operation of voting machines; and my primary object is to provide a restrictive device adapted to coact with the interlock-bars of voting machines, whereby a voter may be prevented from cumulating votes for a candidate nominated by one party and indorsed by another party.

The present application constitutes a division of my application No. 470,411, filed Jan. 2, 1909.

My invention is illustrated in the preferred embodiment in the accompanying drawings, in which—

Figure 1 is a vertical sectional view of a voting machine equipped with my improvements; Fig. 2, a broken rear elevational view of the machine with the rear casing-plate removed; and Fig. 3, a broken view illustrating the key-board arrangement.

It may be stated preliminarily that the general construction of the machine in connection with which my present improvements are illustrated is shown and described in my said application No. 470,411. In this machine the voting mechanism is operated through the medium of vertically disposed shafts, said shafts being turned in one direction to unlock the voting mechanism by an initial operation as the voter passes the machine, and said shafts being turned in the opposite direction to complete the voting operation as the voter passes from the machine after having set the voting keys in position to actuate the voting registers.

The machine illustrated is equipped at one end with a combination locking and actuating device which may be released and initially operated to actuate said shafts and unlock the voting mechanism; and said machine is equipped at the opposite end with a combination actuating and locking device which locks said shafts after their first actuation and which may be released and employed to actuate the shafts in the return movement as the voter passes from the machine, there-

by to complete the voting operation, the voter having in the meantime set the voting keys in position to actuate the vote-registers upon the final operation of the machine. The initial operating handle is capable of being turned in either direction, according to the sex of the voter; and in any event, the shaft will be turned in the same direction, that is, in a direction to unlock the voting mechanism and permit the voting keys to be preliminarily set.

The machine as illustrated comprises a casing A having a front key-board A¹ and a removable rear side A²; register mechanisms B mounted in the machine adjacent to the key-board A¹; voting keys C connected with slides C¹ coacting with said register mechanisms; interlock mechanism D connected with the slides C¹; vertically disposed shafts E carrying horizontally movable bars E¹ which normally lock the slides C¹ against being moved forward through the operation of the voting keys; a combination actuating and locking device F which may be released and then will serve to actuate the shafts E and move the bars E¹ to the forward position, thus permitting the voting keys to be operated to preliminarily set the actuating slides; a combination actuating and locking device G which serves to lock the shafts E after they are preliminarily moved to unlock the voting keys, and which may be released and serve to actuate the shafts E to complete the voting operation, as the voter passes from the machine after having preliminarily set the voting keys; restrictive mechanism H coacting with the interlock bars of the interlock mechanism B and serving in one position to permit restrictive voting by women and in another position to permit unrestricted voting by men, said mechanism H being preparatorily moved when the shafts E are actuated through the medium of the initial actuating device F; a locking and re-setting device I coacting with the interlock bars of the interlock mechanism D; and a device J serving to prevent cumulative voting under conditions where a nominee of one party is indorsed by another party.

The casing A may be of any approved construction, and so, also, may be the vote-registering or tallying mechanisms B. The voting keys C project through the key-board

A^1 and are adapted to actuate or move forwardly horizontally disposed slides 1 which are equipped with spring-pawl 2 adapted to engage the ratchet-wheels of the registering mechanisms, whereby, when the slides are moved backwardly, in the final operation of the machine, the registering mechanisms will be actuated. Links 3 are connected with said slides and with bell-crank levers 4 connected with vertically disposed interlock bars 5 of the interlock mechanism D. The lower ends of the interlock bars 5 extend through guides 6 and are equipped with wedge-members 7, as described in my pending application No. 426080, filed April 9, 1908. The interlock bars 5 are provided with offsets or shoulders 8 and 9, as shown in Fig. 1.

The key-board A^1 of the machine is provided, in accordance with the usual construction, with perforations through which the voting-keys C extend. For convenience, I have shown, in Fig. 3, three horizontal rows of voting-keys, the rows being marked, respectively, "Republican," "Democrat" and "Prohibition." These keys are shown as arranged in vertical rows corresponding with the offices to be filled. I have selected two vertical rows of voting-keys corresponding to a situation where two offices of the same grade or character are to be filled, as, for instance, where two judges are to be elected. In such case, the interlock-bars 5 are arranged to permit the casting of two votes for judges, and this is a case where the device J, for preventing cumulative voting for a candidate nominated by one party and indorsed by another, is applicable. Thus, in Fig. 3, the Republican candidates are designated Roe and Dee; the Democratic candidates Moe and Hoe; and the Prohibition candidates Poe and Roe, Roe being the Republican candidate indorsed by the Prohibitionists. In such case, it is not permissible for a voter to vote twice for the same candidate, and the device J is to prevent such illegal voting.

Each slide 1 is equipped with a link 11 having a lug 12, the link 11 being adapted to be depressed when the slide is moved forwardly through the medium of the key C, thereby to bring the lug into the path of the corresponding bar E^1 forming a part of the slide-retracting mechanism which serves in the final portion of the voting operation.

As has been indicated, the interlock bars 5 of the interlock mechanism D are adapted to be elevated when the voting-keys are drawn forwardly and the slides 1 thereby moved forward.

In the illustration given there are three vertical shafts E employed, one being located near each end of the casing and one near the center of the casing and in the same plane as the other two. The bars E^1

are carried by arms 13 on the shafts E. The shafts are then tied together, so that when one shaft is turned all will be turned simultaneously.

The combination locking and actuating device F is described in detail in my application No. 470411. It is sufficient to state here that it comprises a horizontally disposed shaft 14 equipped with a handle 15, said shaft 14 extending through one end of the casing near the bottom thereof; a gear-segment 16 connected with the inner end of said shaft; bevel-gears 17 and 18 located above and below said gear-segment and fixed on the corresponding shaft E and co-acting with such gear-segment whereby the shaft E may be turned in a given direction, regardless of the direction of movement of the handle 15; and a locking device 19 applied to the casing of the machine and co-acting with the horizontal shaft 14. The device 19 has a handle 20 which may be moved in one direction or the other to enable the shaft 14 to be turned in one direction or the other, depending upon the sex of the voter.

The combination locking and actuating device G is described in detail in said application No. 470411, and it is sufficient to state here that such device is of a character to permit the shafts E to be rotated through the medium of the handle 15, thereby to unlock the voting-keys, and that after the voting-keys have been preliminarily set, the voter, in passing from the machine, may, through the medium of the device G, actuate the shafts E to return them to their normal position, in which operation the final portion of the voting operation is effected.

The mechanism H is described in said application No. 470411. It is sufficient to state here that said device is actuated through the medium of a slide 21 which is connected by a link 22 to the beam or arm 23 carried by the shaft 14. The device H carries adjustable stops 24 adapted to engage the shoulders 8 of the interlock bars when the machine is set for use by a female voter. Thus, the stops 24 may serve to prevent the actuation of all of the interlock bars except those corresponding with the voting-keys which female voters are free to actuate.

The locking and re-setting mechanism I is described in detail in said application No. 470411. It is sufficient to state here that the device may be employed for restoring the voting-keys to their normal position in case the voter makes an error, and said device is also equipped with a lock 25 which is connected with one of the shafts E, so that the lock will be released when the shafts E are preliminarily actuated to release the voting-keys.

The device J, by means of which unauthorized cumulative voting for an indorsed

candidate is prevented, comprises, preferably, a flexible member or cord 26 having its ends equipped with hooks 27; and a guide member 28 through which said cord extends, 5 said member 28 being adjustably connected with a horizontal guide 29 which extends from one end of the machine to the other, at the bottom thereof, and receives the lower ends of the interlock-bars 5. Each interlock-bar is provided with a vertical series of perforations 30 adapted to receive the hooks 27. It will now be understood that the cord 26 may be connected with the interlock-bars 5 corresponding with the voting keys 10 15 voted to an indorsed candidate. Thus, in the illustration given in Fig. 3, the candidate Roe is indorsed by the Prohibition party and thus becomes one of the candidates for the Prohibition party; and as there are 20 two candidates of the same class to be elected for offices for which cumulative voting is not permissible, it is necessary to prevent any voter from voting twice for Roe. Accordingly, the interlock-bar connected with 25 the Roe voting keys are joined by the flexible member 26, sufficient slack being allowed in said member to enable one of the interlock-bars to be raised, but the flexible member being short enough to retract the interlock-bar first raised in the event that the second 30 interlock-bar is raised. The perforations 30 enable the cord to be adjusted to suit conditions, regardless of whether the interlock-bars which it is necessary to connect by the 35 cord are close together or somewhat widely separated. It is usual, of course, to group the interlock-bars for offices of the same class together, but the interlock-bars which are to be connected by the cord may or may not lie 40 side by side.

I have, in Fig. 2, illustrated two of the devices J, associated with different groups of interlock-bars; and I have, in Fig. 3, illustrated two different vertical groups of voting keys corresponding with the offices to 45

which the groups of interlock-bars relate, the names of the candidates appearing. In the second group shown in Fig. 3 the Republican candidate Jones is indorsed by the Prohibition party, so that the interlock-bars 50 corresponding with the J voting keys are joined by the flexible member 26 of the corresponding device J.

The operation will be readily understood. When a voter pulls a voting-key forward, 55 he thereby raises the corresponding interlock-bar 5. The interlock-bars corresponding with the voting-keys devoted to the indorsed candidate are connected by the device J, the flexible connecting medium 60 26 being of sufficient length to enable one interlock-bar to be raised. If, however, the voter attempts to vote twice for the indorsed candidate, the first interlock-bar and voting-key actuated by him will be 65 retracted when the second voting-key is drawn forwardly, this action occurring through the medium of the flexible member 26 which moves through the guide 28.

The foregoing detailed description has 70 been given for clearness of understanding only, hence no undue limitation is to be understood therefrom, but the appended claim should be construed as broadly as is permissible in view of the prior art. 75

What I regard as new, and desire to secure by Letters Patent, is—

In a voting-machine, the combination with voting mechanism, including voting-keys and interlock-bars connected therewith, 80 of an adjustable guide, a flexible member extending therethrough and equipped with hooks connected with certain of said interlock-bars, said interlock-bars having a series of perforations to receive said hooks, for the 85 purpose set forth.

LENNA R. WINSLOW.

In presence of—
D. O. YODER,
EMILIE WINSLOW.
